SAFETY ATTACHMENT

Isaac D. Houseman, Cleveland, Ohio

Application September 10, 1947, Serial No. 773,141

3 Claims. (Cl. 188—65.2)

1

This invention relates to a safety attachment for a workman when employed on a scaffolding or other support operatively disposed at the side of a wall or building structure; where such supporting equipment is used it has been the practice to provide a life line for the workman to manually grasp in the event the scaffold for any reason drops or is displaced. However, it is apparent that if an accident occurs without warning or the workman is beyond the reach of the life line, he will be unable to grasp the latter. The safety attachment herein disclosed provides a connection between the workman and the life line, so that in the event of an accident, such as (a) the scaffold or support and/or its supporting means fall or break, (b) the scaffold or support is displaced (for example, due to the raising of some equipment), or (c) the workman loses his balance and falls off the scaffold, the workman is automatically prevented from falling.

For purposes of illustrating the preferred application of the invention, the workman is shown standing on a scaffold, which may be raised and lowered by suitable block and tackle, associated with a life line attached to and depending from a high point of the wall or building structure and relative to which the scaffold may be adjusted from time to time upwardly or downwardly to change the working elevation, the safety attachment being detachably connected or clamped to the life line so as to be adjusted therewith when the scaffold is moved to a different level in either direction.

One object of the invention is to provide an improved safety attachment for a workman, having co-acting clamping elements for engaging the life line, one of the elements being movable and biased by a spring, whereby the attachment is adjustably connected to the life line, the workman being connected to the movable clamping element so that in the event of an accident the weight of his body operates through this element to effect a positive gripping of the life line by the clamping elements with sufficient pressure or grip to prevent the workman from falling.

Another object of the invention is to provide an improved safety attachment embodying certain improvements in the form of construction shown in my co-pending application Ser. No. 745,566, filed May 2, 1947.

Other objects of the invention will be apparent to those skilled in the art to which my invention relates from the following description taken in connection with the accompanying drawing, wherein

2

Fig. 1 is a fragmentary perspective view of a building structure and a scaffold suspended in operative relation thereto, showing a workman on the scaffold, the workman being connected to the life line by an attachment embodying my invention.

Fig. 2 is a side elevation of the clamping mechanism mounted in adjusted position on the life line, parts being broken away.

Fig. 3 is a top plan view.

Fig. 4 is an end elevation looking toward the right of Fig. 2.

Fig. 5 is an elevational view showing a modification.

15 In the drawing, 1 indicates as an entirety a portion of a building structure. 2 indicates as an entirety a scaffold adjustably suspended by the usual block-and-tackle 3 in operative relation to the structure 1. 4 indicates a safety or life line (preferably consisting of a rope) secured at its upper end to a high point of the structure or other elevated support and depending therefrom to a point adjacent or below the lowest position to which the scaffold may be lowered. 20 The life line 4 is preferably disposed midway between the opposite ends of the scaffold 2 and may be related thereto on its inner or outer side.

The safety attachment consists of a belt 5 suitably bound around the workman's body, a clamping mechanism indicated as an entirety at 6 and a flexible connection 7 (such as a rope or chain) of any desired length detachably connected at its opposite ends to the belt 5 and mechanism 6. The belt 5 may be provided with suitable straps 5a adapted to extend over the workman's shoulders to hold the belt in place; in the event the scaffold drops or the workman falls off therefrom and is suspended by the life line, as later set forth, the straps and belt together support the workman in suspended position without undue binding or pressure effect on his body, as would otherwise result if the belt 5 only were used. The clamping mechanism 6 consists of the following: 8 indicates a bar provided at its upper and lower ends with laterally extending pairs of arms 9, 10, which straddle the life line 4 to maintain it in position at all times, the outer ends of the arms 9 being reinforced by legs 9a. As the pairs of arms 9, 10, are relatively spaced, they guide the mechanism 6 endwise of the life line 4 when being adjusted relative thereto. The parts referred to are preferably formed integrally, but certain elements thereof may be formed separately and welded or otherwise secured together. The inner wall of the bar 8 adjacent to

and below the arms 9 is shaped to provide a clamping element 11, the face of which is of concave shape and suitably knurled to insure frictional contact with the life line 4. By preference, the clamping element 11 consists of a section of metal welded to the bar 8. 12 indicates a rocker of substantially bell-crank shape disposed between the arms 9 and fulcrumed on a pivot pin 13 extending through aligned openings formed in the outer end portions of the arms 9. The pin 13 is provided at one end with a head 13a and with a device 13b—such as a cotter pin—at its opposite end, the head 13a and device 13b serving to limit the endwise movement of the pin but permitting it to be removed for a purpose later set forth. The inner arm 12a of the rocker 12 provides a clamping element to cooperate with the clamping element 11 to engage the life line between them, the outer face of the arm 12a is substantially concave in cross section and knurled to insure adequate frictional contact with the life line 4. The other arm 12b of the rocker 12 is connected to one end of a spring 14. The opposite end of the spring is anchored to a lug 10a integrally connected to one of the arms 10. The spring 14 serves to rock the rocker 12 counterclockwise, as viewed in Fig. 2, and thus effect engagement of the clamping element 12a with the life line 4. As shown the arm 12b is relatively long as compared to the arm 12a to provide adequate leverage in operation and the spring 14 is of a size and strength to maintain the clamping element 12a against the life line and in opposition to the clamping element 11 under pressure to secure the mechanism 6 to the life line 4 in any adjusted position thereof; that is, the frictional engagement of the clamping elements 11 and 12a with life line 4, under the influence of the spring 14, exceeds the tendency of the mechanism 6 due to its weight and that of the connection 7 to gravitate. By swinging or rocking the rocker 12 clockwise, the clamping element 12a is disengaged from life line 4; when the life line 4 is disengaged in this manner, the mechanism 6 may be bodily adjusted endwise of the life line. 15 indicates a link pivotally connected at its upper end to the outer end portion of the rocker arm 12b; this connection is shown as a ring 16, but may consist of a clevis. The link 15 depends downwardly, substantially in the plane of the bar 8 and between the arms 10 to a point below the latter, the lower end of the link 15 terminating in a ring 15a, to which the outer end of the connection 7 is detachably connected by suitable fastening means, such as a snap hook 17. Where a snap hook 17 or other equivalent device is not used, the end portion of the flexible connection 7 may be inserted through the ring 15a and tied into a knot. The link 15 is held within the arms 10 by a pin 18 removably supported in aligned openings formed in the outer end portions of the arms 10. By preference, the pin 18 is provided with a roller 18a to reduce friction on the link 15 during operation thereof to rock the rocker 12. The mounting for the pin 18 is preferably similar to that provided for the pivot pin 13. The pins 13 and 18 are removable so that when initially hanging or connecting the mechanism 6 on the life line 4, the rocker 12, link 15 and roller 18a may be disassembled to permit the life line to be positioned between the arms 9, 10 (as shown), whereupon these parts may be reassembled, thereby eliminating the trouble of reeving the life line in or through the pairs of

arms 9, 10, and between the clamping elements 11, 12a. When the scaffold 2 is to be raised or lowered to a new working elevation, the link 15 is moved upwardly by the workman to rock the 5 rocker 12, clockwise, in opposition to the spring 14, to disengage the clamping elements 11, 12a, from the life line 4; the mechanism 6 is then adjusted endwise thereof to a new position and the link 15 released from the hand or hands of 10 the workman to permit the spring 14 to operate the rocker 12 counter-clockwise, whereby the mechanism is re-engaged with the life line 4 and held in fixed relation thereto.

Operation.—When the mechanism 6 is initially connected to the life line, as above set forth, it is adjusted thereon to the desired height. The workman may then don the belt 5 and attach the flexible member 7 to the belt and to the ring 15a to insure his safety. In the event of 15 an accident, such as herein referred to, it will be evident that the weight of the workman's body will exert a downward pull through the connection 7 and link 15, and the latter will rock the rocker counter-clockwise and cause an increased gripping effect by the clamping elements 11, 12a, on the life line 4, and hence prevent the workman from falling beyond a level limited by length of the connection 7 from the position of the mechanism 6.

30 Fig. 5 shows a modified form of construction, wherein the upper end of the link 15 is provided with bifurcations 15b which straddle the arm 12b of the rocker 12 and are pivotally and removably connected thereto by the pin 13.

35 To those skilled in the art to which my invention relates many changes in construction and widely differing embodiments and applications of the invention will suggest themselves without departing from the spirit and scope thereof. My disclosures and the description herein 40 are purely illustrative and are not intended to be in any sense limiting.

What I claim is:

1. In safety means for a workman while working on a scaffold, the combination with a safety line, of a mechanism arranged to be adjustably supported on said safety line, said mechanism consisting of a vertically disposed bar provided with upper and lower aligned pairs of laterally 45 extending arms through which the safety line extends, a lever fulcrumed on and between said upper pair of arms, clamping elements carried by said bar and the inner arm of said lever in opposed relation and arranged to engage and 50 disengage said safety line, a spring connected to the outer arm of said lever and arranged to swing said lever in a direction to effect engagement of said elements with said safety line under pressure, whereby said mechanism is adjustably fixed to and supported on said line, and an operating 55 rod pivotally connected to the outer arm of said lever and depending therefrom and through said lower pair of arms and guided thereby and adapted to be connected to the workman, said 60 rod when moved in a direction in opposition to the tension of said spring serving to disengage the clamping elements from the safety line and when moved in the opposite direction due to the weight of the workman in falling, serving to effect a rigid clamping engagement of the clamping elements with said safety line, whereby the workman is held in a suspended position on said safety line.

2. In safety means for a workman while working on a scaffold, the combination with a safety

line, of a mechanism arranged to be adjustably clamped to the safety line, said mechanism consisting of a vertically disposed bar provided with upper and lower aligned pairs of laterally extending arms through which the safety line extends, a lever fulcrumed on and between said upper pair of arms, clamping elements carried by said bar and the inner arm of said lever in opposed relation and arranged to engage and disengage said safety line, a spring connected to the outer arm of said lever and arranged to swing said lever in a direction to effect engagement of said clamping elements with said safety line under pressure, whereby said mechanism is adjustably fixed to and supported by said line, an operating rod pivotally connected to the outer arm of said lever and extending therefrom through said lower pair of arms and adapted to be connected to the workman, said rod when moved in a direction in opposition to the tension of said spring serving to disengage the clamping elements from said safety line and when moved in the opposite direction due to the weight of the workman in falling serving to effect a rigid clamping engage-

ment of said clamping elements with said safety line, whereby the workman is held in a suspended position on said safety line, and a device supported at its opposite ends in the outer ends of said lower pair of arms and cooperating with the latter to guide said rod when it is moved in either direction.

3. A safety means as claimed in claim 2, wherein the fulcrum for said lever and the said guide device for said operating rod are removable.

ISAAC D. HOUSEMAN.
